UNITED STATES PATENT OFFICE.

HARVEY J. LIPHAM, OF CREAMERY, PENNSYLVANIA.

CONCRETE RAILROAD TIE.

Application filed June 19, 1926. Serial No. 114,926.

My invention relates to new and useful improvements in a concrete railway tie, and has for its object to so construct such a tie that it will consist of three elements; viz, 5 two support blocks and a reach bar, the blocks being readily attached to or detached from the bar to facilitate the construction, transportation and installation.

A further object of my invention is to 10 produce composite support blocks for the tie, which blocks shall consist of a supporting beam, reenforcement rods, supporting rods coacting with the supporting beam, re-enforcement rods upon which the supporting 15 rods are seated, an enclosure of stranded cables surrounding the support rods, all being embedded in plastic material, such as concrete or cement; thus providing an effective indestructible support for the railway 20 rails.

A still further object of my invention is to provide an effective means for the securing 25 of railway rails upon the support blocks.

With these and other ends in view, this invention consists in the details of construction and combination of elements hereinafter set forth and then specifically defined by the 30 claims.

In order that those skilled in the art to which this invention appertains, may understand how to make and use the same, I will describe its construction in detail, referring by numerals to the accompanying 35 drawings forming a part of this application, in which:

Fig. 1 is a side elevation of a tie made in accordance with my improvement showing the rails secured thereon.

Fig. 2 is a plan view of Fig. 1, showing several of the ties.

Fig. 3 is an enlarged plan view of one of the supporting blocks forming a part of my improved tie.

Fig. 4 is a side elevation of Fig. 3, the concrete being in section, and the railway rails shown secured upon the supporting block.

Fig. 5 is an end view of Fig. 4, the concrete also being in section, the rail and its 50 fastenings being omitted.

Fig. 6 is a view similar to Fig. 5, showing the addition of an envelope of expanded metal, such as used in metal lath.

In carrying out my invention as herein 55 embodied, each of the supporting blocks 10 in construction consists of a supporting

beam 11, here shown as what is known as an H-beam, or it may be of any other suitable shape, such as an I-beam or a T-beam, and to the underside of the head of this beam are 60 welded, riveted, bolted, clamped or otherwise fastened the upper ends of a series of supporting rods 12, said rods extending downward in the general shape of a U, and crosswise beneath the base of the beam and 65 being welded to said base.

13 represents a series of stranded cables or the continuation of a single cable, surrounding the supporting rods, in such manner as to form a cage or enclosure for cement. 70

14 represents a series of reenforcement rods upon which the supporting rods are seated, as clearly shown in Figs. 5 and 6, and this enclosure and these reenforcement rods are embedded in cement 15, or other 75 suitable material; thus producing a reinforced block, all of the metal parts of which are encased in cement, with the exception of the upper surface of the head of the supporting beam, thereby giving the block necessary 80 width and length to sustain the weight and vibration incident to the travel of trains thereon, when said block is properly set in the road bed, and also preventing the oxidizing or corrosion of the metal parts. 85

Prior to embedding the metal structure of the support block in cement, a clip 16, preferably in the form of an angle iron, is secured by rivets, bolts or welding to the web of the support beam in such manner that 90 after the metal structure is embedded in the cement, a portion of this clip will extend beyond one end of the completed block, as clearly shown. The extending ends of these clips are adapted to receive the ends of the 95 reach bars 17, which latter are also preferably in the form of angle irons which may be set over the clips or beneath the same, and securely held in place by the bolts 18 and 19, and when two of the support blocks 100 are coupled together by one of these reach bars, a completed tie is produced which for the purpose of transportation or installation may be disassembled by uncoupling the blocks from the reach rod and reassembled 105 by again coupling the three elements together.

In making provision for the proper securing of the railway rails 20 upon the ties, threaded holes are formed through the 110 head of the supporting beams and nuts 21 embedded in the cement so as to coincide

with these threaded holes whereby the bolts 22 may not only be threaded into and through said holes, but also be threaded into said nuts, and in practice, these nuts may be made 5 of material of much higher tensile strength than the support beams, thus increasing the hold of the bolts to the beam. These bolts pass through suitable holes in the clamp blocks 23, said blocks being of such shape 10 that they readily fit over the flanges of the rails 20, as clearly shown in Fig. 4, so that by jamming these bolts home, the rails will be firmly held against sidewise movement incident to the thrust of the car wheels traveling over the rails.

I have shown the completed blocks in the general shape of the frustum of a pyramid, but they may be of any suitable shape, the principal object being to secure a wide bottom surface for sustaining the weight to 20 which the blocks are subjected while holding them against sidewise or upward movements.

In Fig. 6, I have shown a slight modification of my invention, in which a casing or 25 envelope 24, preferably of expanded metal, similar to that used for metal lathing surrounds the stranded cables 13, in order that when the frame work of the supporting block is embedded in its cement, that portion 30 of the cement which passes through the casing will be housed therein, and thus further reduce the tendency to shatter or fracture such concrete, when the block is subjected to severe pounding.

Suitable holes 25 are formed in the clip 16 for the passage of the cables 13 through said clip.

Of course I do not wish to be limited to the exact details of construction as herein 40 shown as these may be varied within the limits of the appended claims without departing from the spirit of my invention.

Having thus fully described my invention, what I claim as new and useful is:

45 1. A railway tie comprising two composite support blocks and a reach rod for spacing said blocks apart and securing them together, each of said composite blocks consist-

ing of a supporting beam, a series of supporting rods, the ends of which latter are 50 secured to the head of said beam, said rods extending beneath the base of said beam, cables surrounding the supporting rods, reinforcing rods upon which the lower portion of the supporting rods are seated, all of said 55 parts being embedded in a suitable plastic material; and a clip secured to the web of the supporting beam and projecting beyond the plastic material for attachment to the reach rod.

2. A composite block for railway ties comprising a supporting beam; supporting rods the ends of which are secured to the head of said beam, the lower portion of said rods extending beneath the base of said beam; an 60 openwork enclosure surrounding the supporting rods; reinforcement rods positioned beneath the supporting rods; a block of cement embedding said structure; and a clip 65 secured to the web of the supporting beam and projecting beyond the cement block for coupling the block to a companion block for the formation of a tie.

3. A composite block for railway ties comprising a supporting beam; supporting rods the ends of which are secured to the head of said beam, the lower portion of said rods extending beneath the base of said beam; an 70 openwork enclosure surrounding the supporting rods; reinforcement rods positioned 75 beneath the supporting rods; a block of cement embedding said structure; a clip secured to the web of the supporting beam and projecting beyond the cement block for coupling the block to a companion block for the 80 formation of a tie; threaded holes formed through the head of the supporting beam; nuts embedded in the cement block coinciding with said threaded holes; two clamp blocks positioned upon the head of the beam; 85 and bolts passing through holes in said block and threaded into said threaded holes and nuts.

In testimony whereof, I have hereunto affixed my signature.

HARVEY J. LIPHAM.
